United States Patent Office

Des. 183,363

Patented Aug. 12, 1958

183,363

PHOTOGRAPHIC SLIDE BINDER OR SIMILAR ARTICLE

Clarence B. Mitchell, Chicago, Ill., and Herbert R. Leopold, Havertown, Pa., assignors to Optics Manufacturing Corporation, Philadelphia, Pa., a corporation of Illinois

Application September 30, 1957, Serial No. 47,921

Term of patent 14 years

(Cl. D61—1)

FIG. 1

FIG. 3

FIG. 2

Fig. 1 is a front perspective view of a photographic slide binder or similar article, showing out new design;

Fig. 2 is a front elevational view, the rear being substantially a mirror image thereof; and

Fig. 3 is a side elevational view, the opposite side being substantially a mirror image thereof.

A portion of the drawing figures is diagonally lined to indicate transparency.

We claim:

The ornamental design for a photographic slide binder or similar article, as shown and described.
